COMBINED STORAGE AND DISPLAY RACK
PRIMARILY FOR TAPE CASSETTES

Richard Roy Rumble, 47 Orchard Court, Portland Square,
London W.1, England

Filed Mar. 8, 1974, Ser. No. 449,549

Claims priority, application Great Britain Jan. 3, 1974

Term of patent 14 years

Int. Cl. D6—04

U.S. Cl. D6—29

FIG.1

FIG.4

FIG. 5

FIG. 6

FIG. 1 is a side elevational view of a combined storage and display rack primarily for tape cassettes showing my design;

FIG. 2 is an end elevational view;

FIG. 3 is a top plan view;

FIG. 4 is a bottom plan view;

FIG. 5 is a sectional view taken along the lines 5—5 of FIG. 3; and

FIG. 6 is a perspective view thereof.

The side not shown in FIG. 1 is like the side shown while the end not disclosed in FIG. 2 is a mirror image of the end disclosed.

I claim:

The ornamental design for a combined storage and display rack primarily for tape cassettes, as shown and described.
